UNITED STATES PATENT OFFICE.

ISADOR LEHMAN, OF CLEVELAND, OHIO.

POWER-TRANSMITTING MECHANISM.

SPECIFICATION forming part of Letters Patent No. 730,936, dated June 16, 1903.

Application filed March 16, 1903. Serial No. 148,031. (No model.)

To all whom it may concern:

Be it known that I, ISADOR LEHMAN, a citizen of the United States of America, residing at Cleveland, in the county of Cuyahoga and State of Ohio, have invented certain new and useful Improvements in Power-Transmitting Mechanisms; and I hereby declare the following to be a full, clear, and exact description of the invention, such as will enable others skilled in the art to which it pertains to make and use the same.

This invention relates to improvements in power-transmitting mechanism suitable for use in transmitting power from a reciprocating member to any movable member or object, and pertains more especially to such an operative connection between the said reciprocating member and the crank of a crank-shaft that the length of the reciprocations of the said reciprocating member and the connected pitman are materially shorter than would be the case if the said pitman were directly connected with the said crank.

With this object in view, and more especially to advantageously arrange the different parts of the mechanism, this invention consists in the certain peculiarities of construction and arrangement and combination of parts hereinafter described, and pointed out in the claims.

In the accompanying drawings, Figure 1 is a side elevation, largely in central longitudinal section, of my improved power-transmitting mechanism arranged to transmit power from the piston of the cylinder of an engine to the crank of the engine-shaft. Fig. 2 is a top plan of the same.

Referring to the drawings, *a* designates the cylinder of an engine; *b*, the piston, contained within and adapted to operate endwise of the interior chamber of the cylinder; *c*, a cross-head or slide with which the outer end of the piston-rod *d* is provided externally of the cylinder, and *G* slideways or guides engaged by the said slide or reciprocating member. A pitman *f* is pivoted horizontally and transversely at one end, as at *h*, to the reciprocating member *c* and pivoted horizontally and transversely at its other end, as at *k*, to the upper of two approximately parallel rods *l* and *o*, arranged one above the other.

A depending rock-arm *p* is arranged with

its axis between the path of the reciprocating member *c* and the engine-shaft *r*, which is a crank-shaft whose crank *s* is operatively attached to an oscillating lever *m*, which centrally between its ends loosely embraces the wrist *t* of the said crank. The shaft *r* and the path of the reciprocating member *c* are arranged at right angles to each other, and the said shaft and the said path and the axis of the rock-arm *p* are preferably arranged at the same elevation. It will be observed that the lever *m* extends below, as well as above, the wrist *t*. The upper rod *l* is pivoted horizontally and transversely, as at *n*, to the upper end of the lever *m*, which is fulcrumed, as at *u*, at its lower end and below the wrist *t*, horizontally to and transversely of the lower rod *o*. Preferably the arrangement of the parts is such that the lower extremity of the lever *m* is as far below the wrist *t* as the upper extremity of the lever is above the said wrist. Hence the rods *l* and *o* are arranged equidistant from the wrist *t* at opposite sides, respectively, of the said wrist, and consequently the load upon the crank of the crank-shaft or object to be driven is advantageously distributed.

The lower rod *o* is pivoted horizontally and transversely, as at *w*, to the lower end of the rock-arm *p*. The upper rod *l* is pivoted horizontally and transversely, as at *x*, to the arm *p* between the rod *o* and the axis of the said arm.

The rock-arm *p* is provided at its upper end with trunnions *y*, which are arranged parallel with the crank-shaft and have bearings in boxes *e*, with which any suitable support—such, for instance, as the stationary framework of the engine—is provided. The upper portion of the rock-arm *p* is recessed or cut away, as at *j*, to accommodate the location and operation of the pitman *f*, and the upper rod *l*, where the pitman is attached thereto—namely, at the pivot *k*—is offset downwardly, as at *L*, to accommodate the location and operation of a pitman *f*, which terminates in a short fork *g*, straddling the said rod and pivoted to the said rod at *k*.

By the construction hereinbefore described it is obvious that power is transmitted to the crank *s* from the pitman *f* through the medium of the upper rod *l* and the lever *m* and

that the depending rock-arm *p* and the lower rod *o* are instrumental in guiding the upper rod *l* and the lever *m* during the transmission of power to the said lever.

5 Although I have particularly described and illustrated mechanism for transmitting power from a reciprocating member to a crank-shaft, I would have it understood that my invention embraces, broadly, the use of the said mechanism in transmitting motion from the reciprocating member *c* to any movable body or object to which power is to be transmitted from the said reciprocating member.

What I claim is—

15 1. The combination, with a reciprocating member; means for actuating the said reciprocating member; means for guiding the said reciprocating member, and a movable body or object to which motion is to be transmitted from the said reciprocating member, of an oscillating lever operatively attached to the aforesaid movable object or body to which motion is to be transmitted and arranged a suitable distance from the path of the aforesaid reciprocating member, which lever extends in opposite directions from the point of its attachment to the object to be actuated thereby; a rock-arm arranged between the lever and the said path; two approximately parallel rods establishing operative connection between the rock-arm and the lever, which rods are arranged at opposite sides respectively of the aforesaid point of attachment, and a pitman operatively attached, at 35 one end, to one of the said rods in suitable proximity to the lever and operatively connected, at its other end, with the aforesaid reciprocating member.

2. The combination, with a reciprocating member; means for actuating the said reciprocating member, means for guiding the said reciprocating member, and the crank of a crank-shaft arranged a suitable distance from the path of the reciprocating member, of an oscillating lever operatively attached to and at the wrist of the crank and extending above and below the said wrist; a depending rock-arm arranged a suitable distance from the lever between the shaft and the aforesaid path; two approximately parallel rods pivotally attached to the upper end and lower end respectively of the lever and operatively at-

tached to the rock-arm at different elevations respectively, and a pitman operatively attached to the upper rod near the lever and 55 operatively connected with the aforesaid reciprocating member.

3. The combination, with a reciprocating member; means for actuating the said reciprocating member; means for guiding the said reciprocating member, and a movable body or object to which motion is to be transmitted from the said reciprocating member, of an upright oscillating lever operatively attached, centrally between its ends, to the 65 aforesaid object or body to which motion is to be transmitted, which lever is arranged a suitable distance from the path of the aforesaid reciprocating member; a rock-arm arranged near the said path; two approximately parallel rods extending between and pivoted horizontally and transversely to the lever and to the rock-arm, which rods are arranged, at the points of their attachments to the lever, equidistant from the wrist of the crank, and a pitman operatively attached, at one end, to the 70 upper rod and operatively connected, at its opposite end, to the aforesaid reciprocating member.

4. Power-transmitting mechanism comprising an oscillating lever operatively engaging a movable body or object to which motion is to be transmitted, a rock-arm arranged a suitable distance from the lever, two approximately parallel rods extending between and pivoted horizontally and transversely to the lever and to the rock-arm, and a suitably-actuated pitman operatively connected with one of the said rods, and the pitman-engaging rod being offset where the pitman is attached thereto toward the other rod, and the arrangement of the parts being such that motion is transmitted to the lever from the pitman through the medium of the rod to which the said pitman is attached and that the rock-arm and the other rod coöperate as a guide.

In testimony whereof I sign the foregoing specification, in the presence of two witnesses, this 12th day of March, 1903, at Cleveland, Ohio.

ISADOR LEHMAN.
